ELECTRIC TIME ALARM.

No. 585,480.

Patented June 29, 1897.

UNITED STATES PATENT OFFICE.

ALVAH CURTIS ROEBUCK, OF CHICAGO, ILLINOIS.

ELECTRIC TIME-ALARM.

SPECIFICATION forming part of Letters Patent No. 585,480, dated June 29, 1897.

Application filed July 27, 1896. Serial No. 600,698. (No model.)

To all whom it may concern:

Be it known that I, ALVAH CURTIS ROEBUCK, of Chicago, in the county of Cook and State of Illinois, have invented a new and Improved Time-Alarm, of which the following is a full, clear, and exact description.

The object of the invention is to provide a new and improved time-alarm more especially designed for use on alarm-clocks to give signals and alarms, and also designed for use in offices, shops, schools, &c., to operate electric bells, buzzers, steam-whistles, and the like to announce the commencement and closing hours for work, study, recreation, &c.

15 The invention consists principally of a graduated disk rotated by clockwork and moving in conjunction with the minute-hand to close an electric circuit containing an alarm or signal.

20 The invention also consists of certain parts and details and combination of the same, as will be fully described hereinafter and then pointed out in the claims.

Reference is to be had to the accompanying 25 drawings, forming a part of this specification, in which similar characters of reference indicate corresponding parts in all the figures.

Figure 1 is a front elevation of the improvement applied to the dial of a clock. Fig. 2 is a side elevation of the same. Fig. 3 is a plan view of the lever carrying the contact-point, part being in section. Fig. 4 is an enlarged transverse section of the graduated disk and one of the adjustable arms attached to the 35 disk. Fig. 5 is a perspective view of the attachment for sounding alarms in different locations and at different times. Fig. 6 is a face view of an arm to be used to make contact instead of the hour-hand. Fig. 7 is a face view 40 of a modified form of disk. Fig. 8 is a transverse section of the same. Fig. 9 is a face view of a modified form of the improvement. Fig. 10 is a plan view of the contacting-spring for the minute-hand, and Fig. 11 is a side elevation of the contact-button.

The time-alarm is provided with a clock A, of any approved construction and having a center arbor B, carrying a minute-hand B', and a cannon-pinion C, carrying the hour-hand C'. On the cannon-pinion C is secured a gear-wheel D, in mesh with a gear-wheel E, having twice as many teeth as the gear-wheel

D and having its hub E' mounted to rotate on an insulated stud E², secured to the framework of the clock A.

On the front end of the hub E' is secured a disk F, formed at its face with a graduation F', representing the twenty-four hours of the day, as plainly indicated in Fig. 1, it being understood that the said disk F makes one revolution for every two revolutions of the cannon-pinion C and the hour-hand C', owing to the size of the gear-wheels D and E, as above mentioned.

On the rim of the disk F are held adjustable arms G, each preferably made U-shaped, with the front member provided with a set-screw G' for securing the arm G to the disk F, the end of the set-screw being adapted to pass into an annular groove formed in the 70 face of the disk to securely hold the arm in place, as plainly illustrated in the drawings.

The front member of the arm G is formed into a pointer G², adapted to indicate on the graduation F' the hour at which the signal is 75 to be set or the alarm is to be sounded. The rear member G³ of each arm G is adapted to engage a friction-roller H', held on one end of a lever H, fulcrumed at H² to a bracket secured to the framework of the clock A, the 80 said lever being formed at its upper portion into a spring H³, the extreme upper end of the lever carrying an insulated block H⁴, in which is embedded a contact-point H⁵, connected with an insulated wire I, leading to 85 one pole of a battery or other source of electricity.

A spring H⁶ presses the lever H to hold the latter in a rearward position, as illustrated in Fig. 2, the friction-roller H' then resting 90 against the rear face of the disk F. Now when the member G³ of the arm G comes in contact with the friction-roller H' then a swinging motion is given to the lever H, whereby the upper end of the lever is moved forward into the path of a contact-point B², 95 formed on the minute-hand B', thereby effecting an electric contact and closing the circuit, as hereinafter more fully described.

The block H⁴ projects through an opening 100 in the dial of the clock to bring its point H⁵ into the path of the contact-point B², the latter being secured to the rear face of the minute-hand, as indicated in Fig. 2. The other

wire I', connected with the other pole of the battery or other source of electrical supply, connects with a contact-plate J, insulated on the frame of the clockwork A, the said contact-plate being of spring metal and formed at its free end with a contact-point J', riding on the peripheral surface of a disk J², mounted to rotate on a stud secured to the frame of the clockwork A. On the face of this disk J² is secured or formed a ratchet-wheel J³, having seven teeth adapted to be engaged by a pin D', secured on the gear-wheel D, so that it requires seven revolutions of the latter to give one complete turn to the ratchet-wheel J³ and its disk J². One-seventh part J⁴ of the periphery of the disk J² is covered by a non-conducting plate, so that during the time the contact-point J' rides over the said plate then the circuit is kept open, even should a contact be made between the points H⁵ and B², but as long as the contact-point J' rides over the remainder of the periphery of the disk J² then the circuit is closed whenever the contact-points H⁵ and B² contact with each other, as the current passes by the wire I' through the framework of the clock to the minute-hand B'. Now it will be seen that this plate J⁴ is to represent "Sunday" of the week, so that during Sunday the alarm and signals are not sounded or displayed. It is understood that this device for cutting out one day in the week can be omitted, the wire I' then being simply connected with the framework of the clock A. Now it is evident that the operator can set the arms G to such hour and subdivision at which the signal is to be displayed or the alarm to be sounded, it being understood that the arm at the proper time acts by its member G³ on the lever H to bring the contact-point H⁵ in the path of the contact-point B², so that the minute-hand B' in moving into the proper position to make the contact causes a closing of the circuit and the sounding of the alarm and a display of the signal. Any desired number of such arms may be held on the disk F to sound the alarm at different times of the day. Thus, for instance, as illustrated in Fig. 1, an alarm is sounded at eight a. m., at twelve m., at one p. m., and at six p. m., thus indicating that the factory opens, for instance, at eight o'clock in the morning, closes at noon, opens at one in the afternoon, and again closes at six in the afternoon. The arms thus set remain in this position until it is desired to make a change in sounding the alarm.

In order to be enabled to sound signals in different locations at different times from the same clock, I provide the lever H with an insulated block H⁷, (see Fig. 5,) in which are set a number of contact-points H⁸, adapted to be engaged by arms secured on the center arbor B, the said arms being set to the desired times, and each arm is adapted to make contact with one of the points H⁸ to close the

circuit leading to a certain locality. Each contact-point H⁸ is for this purpose connected with a separate wire I², leading to the desired place. 70

When several signals are to be sounded between the even hours, then I provide one or more arms K, held on the center arbor B, and use them instead of the minute-hand B' for making contact at the point H⁵. The minute-hand B' in this case is insulated to prevent it from making contact. 75

For alarm-clocks on which but one signal is to be used during the twenty-four hours I provide a disk F², mounted to rotate loosely 80 on the hub E³, the said disk carrying an adjustable arm F³ for engagement with the friction-roller H' to shift the lever H, as previously explained. The graduated disk F⁴ is firmly secured to the hub E³ and on it indicates a pointer F⁵, formed integral with the disk F². 85

In the modified form shown in Fig. 9 the arrangement is more especially designed for alarm-clocks of cheap construction and in 90 which the interference from the friction created by the contact-points making connection more than once would not be a serious objection.

On the cannon-pinion is secured a gear-wheel D² in mesh with a gear-wheel E⁴, carrying on its face a graduation E similar to the graduation F'. An arm L is adapted to be secured on this gear-wheel E⁴, and on the arm is formed an opening L', through which 100 appears one of the numerals of the graduation to indicate the hour to which the arm L is set. The outer end of the arm which is carried around by the gear-wheel E⁴ is adapted to make contact with the contact-point N', 105 held on a spring-plate N, insulated from the framework of the clock, the said spring-plate being connected by a wire I³ with one pole of the battery, the other wire I⁴ being connected with the dial A² of the clockwork, and which 110 dial is insulated from the framework. The minute-hand B' in this case is provided with a spring-band B⁴, formed with a contact-point B⁵, (see Fig. 10,) adapted to engage a contact-point O, held on a button O', secured to 115 an arm O², adapted to be secured to the dial A² at the desired time, so that when the minute-hand B' passes over the said arm O², the contact-points B⁵ and O contact to close the circuit, provided the arm L has at the same 120 time made contact with the point N'. 125

It is understood that by the special construction described and shown in Figs. 1 and 2 the minute-hand only makes contact at the time the signal is to be displayed or the alarm is to be sounded, while during the remainder of the time the minute-hand is free to move without any hindrance whatever, the same as in ordinary clocks, so that interference with the rate of speed of the clock by reason of 130 friction is entirely avoided. It will be further seen that by the arrangement described

the attachment can be readily set and adjusted accurately, so that the signal or alarm is given at the correct time.

The device can be readily set for any hour and minute or the fraction of a minute, if desired. The length of the contact can be adjusted to suit the requirements by making the size of the contact-points accordingly.

The attachment is automatic in every respect and requires no attention save the renewal of the batteries.

Having thus described my invention, I claim as new and desire to secure by Letters Patent—

15 1. A time-alarm, comprising a graduated dial driven by clockwork and carrying adjustable arms adapted to be set to the time when the alarm is to be sounded, and a lever adapted to be actuated by the said arm, to move a contact-point on the said lever in the path of the contact-point on the minute-hand of the clock, to close the circuit, substantially as shown and described.

25 2. In a time-alarm the combination of a timing mechanism, signal-controlling disk rotated thereby one complete revolution a day, contact-pieces adjustably attached thereto with a lever placed in a normally open circuit and adapted to be engaged by said adjustable contact-pieces to move its other end into the path of the contact-arm and said contact-arm adjustable in relation to and revolving with the minute-hand, substantially as described.

35 3. A time-alarm, comprising a gear-wheel on the cannon-pinion of a clock, a disk driven from the said gear-wheel and having a graduation indicating the hours of the day, the said gear-wheel making two revolutions to one revolution of the said disk, arms adjustably held on the said disk, a lever adapted to be engaged by the said arms, a contact-point ear-

ried by the said lever, and a second contact-point carried by the minute-hand of the clock, substantially as shown and described.

4. A time-alarm, provided with a lever 45 adapted to receive a swinging motion at a given time, the said lever being provided with an insulated block having one or more contact-points, and a hand or arms driven by clock-work and adapted to make contact with the 50 said contact-points, substantially as shown and described.

5. In an electric time-signaling mechanism, the combination of a timing mechanism, a movable contact-piece having a fixed position 55 upon the dial, and means for setting the same forward, comprising a revolving disk having adjustable cam-blocks thereon, with an arm adapted to engage said movable contact-piece to close the circuit and adjustably connected 60 to and revolving with the minute-hand of the timing mechanism, substantially as described.

6. In an electric time-signaling mechanism, the combination of a timing mechanism, a movable contact-piece having a fixed position 65 upon the dial, and means for setting the same forward, comprising a revolving disk having adjustable cam-blocks thereon, with an arm adapted to engage said movable contact-piece to close the circuit and adjustably connected 70 to and revolving with the minute-hand of the timing mechanism, and a wheel normally forming a part of the circuit and receiving a fractional revolution for each complete revolution of the cam-blocks, and an insulated 75 segment covering one or more of said fractional revolutions and adapted to break the circuit, substantially as described.

ALVAH CURTIS ROEBUCK.
